UNITED STATES PATENT OFFICE.

KARL SCHNEIDER, OF JERSEY CITY, NEW JERSEY.

DISTANCE-INSTRUMENT.

SPECIFICATION forming part of Letters Patent No. 367,067, dated July 26, 1887.

Application filed December 14, 1885. Serial No. 185,565. (No model.)

To all whom it may concern:

Be it known that I, KARL SCHNEIDER, of Jersey City, in the county of Hudson and State of New Jersey, have invented a certain new and useful Improvement for Measuring-Instruments, of which the following is a specification.

The object of my improvement is to provide a simple instrument whereby the distance of objects may be easily ascertained.

I will describe in detail a measuring-instrument embodying my improvement, and then point out the novel features in a claim.

In the accompanying drawings, Figure 1 is a top view of an instrument embodying my improvement. Fig. 2 is a side view of the same. Fig. 3 is a transverse section thereof.

Similar letters of reference designate corresponding parts in all the figures.

Referring to the drawings, A designates a tripod or stand, which may be of any suitable construction. On it is mounted a pillar, B, which may be made of any appropriate metal. In the upper end of this pillar is a seat for a ball, C, forming part of a pedestal, C'. The seat in the pillar corresponds to the part of the ball which it accommodates; hence the pedestal and pillar are connected by a ball-and-socket joint. The pedestal may consequently be adjusted at any angle to the pillar, and may also be rotated relatively to the pillar. The upper end of the pillar is provided with a ring, B', which surrounds the upper part of the ball C and screws into the pillar.

This ring can be manipulated so as to clamp the ball for the purpose of securing the pedestal in any position into which it may be adjusted. In order to get the ring over the ball C, the pedestal is made in two sections, secured together by a screw, C'.

D designates a frame consisting of two arms, d' d'', and cross-pieces d''' d'''. The arm d' is affixed to the pedestal C'. The arm d'' has an arm, E, pivotally connected to it by a screw, e, which also serves as a means whereby the arm E may be clamped in position, providing no other means are employed for that purpose. The cross-piece d''' is made in the shape of an arc of a circle which is concentric with the pivot-screw e, on which the arm E is capable of swinging. It is marked with a scale, and the arm E is provided with an index, e', which

will swing over the scale when the arm E is adjusted. The arm d' has standards f' f'' at the ends, constituting sighting instrumentalities. 55 The standard f' at the rear end has a peep-hole, and the standard f'' at the forward end has a vertical slot intersected vertically by a string. To sight an object the frame D is turned till the peep-hole, the string, and the object to be sighted are in line, whereupon the frame will be secured in position.

The arm E is provided at the ends with standards g' g'', which, like the standards f' f'', are provided, the rear one with a peep-hole 65 and the front one with a vertical slot intersected vertically by a string.

After the sighting is done with the arm d', as above described, the arm E is adjusted so that the same object will be sighted with it. 70 The arm E will preferably be adjusted by a micrometer-screw, G, supported in an oscillating bearing, h', mounted on the arm d', and engaging with an oscillating nut, h'', mounted on the arm E. When the sighting has been 75 done, the arm E will be at an angle to the arm d'. The degree of the angle of the inclination of these arms will indicate the distance of the object sighted.

The scale on the cross piece d''' of the frame 80 D may be made to indicate the degree of the angle between the two arms, or it may be marked so that distance may be read from it.

H designates a compass, which is arranged upon the frame D concentrically with the pedestal C'. Adjacent to this compass are two spirit-levels, I' I'', situated at about right angles to each other, and shown as attached to the case of the compass. These levels are useful, because they provide means whereby the 90 adjustment of the frame D into a true horizontal plane may be readily ascertained.

The compass is useful, because it provides for adjusting the frame D while in a horizontal plane into any desired relation with a certain point of the compass—as, for instance, the relation of an object whose distance is to be measured, but which is not clearly in view, and consequently difficult to find, may be cited by means of adjusting the frame D at a certain angle to an object which is more clearly discernible and whose relation to the object less easily discerned is known.

The needle of the compass is supported or-

dinarily upon an upright pin, *i*, that is arranged within the pedestal *C*, so as to be capable of adjustment lengthwise thereof. The pin is supported upon a shaft, *i'*, that extends transversely through the pedestal *C*, and is provided at one end with a handle, whereby it may be turned, and in the middle with a groove forming an eccentric or cam surface. The rod *i* rests upon the eccentric or cam surface of the shaft *i'*; consequently by rotating the shaft *i'* the rod may be raised or lowered. When it is raised, it will support the compass-needle; but when it is lowered it will allow the compass-needle to descend upon a hub-like seat, *i²*, which is formed upon the bottom of the compass-case, and then the needle will no longer vibrate. This is advantageous, because, after the frame *D* has once been set with reference to the compass, it is undesirable that there should be any vibration of the needle.

25 My improvement may be used in a survey-

or's level or leveling-rod or in a surveyor's transit.

What I claim as my invention, and desire to secure by Letters Patent, is—

25 The combination of a frame comprising an arm provided with sighting instrumentalities, a support with which the frame is connected by a universal joint below the said arm, a compass arranged above the support and arm and concentric with the universal joint, a compass-needle, a vertically-movable pin upon which said needle is supported, a shaft by which said pin is supported, an eccentric or cam surface on said shaft, upon which said rod rests, and a handle for turning said shaft, substantially as and for the purpose specified.

KARL SCHNEIDER.
